UNITED STATES PATENT OFFICE.

FRANK J. SCHLEICHER, OF ST. LOUIS, MISSOURI.

DESIGN FOR A CANDY BOX.

Application filed July 11, 1927. Serial No. 22,721. Term of patent 3½ years.

To all whom it may concern:

Be it known that I, FRANK J. SCHLEICHER, a citizen of the United States, residing at the city of St. Louis and State of Missouri, have invented a new, original, and ornamental Design for Candy Boxes, substantially as shown in the accompanying drawing.

The drawing is a perspective view showing my new design of candy box.

I claim:

The ornamental design for a candy box, substantially as shown.

FRANK J. SCHLEICHER.
